[57] CLAIM

The ornamental design for live poultry mover, as shown and described.

DESCRIPTION

FIG. 1 is an elevation of the live poultry mover embodying my design, an intermediate portion being broken away and omitted to indicate indeterminate length. FIG. 1 A is an opposite side elevation thereof, an intermediate portion being broken away and omitted.

FIG. 2 is a plan view of the live poultry mover shown in FIG. 1 having a corresponding intermediate portion broken away and omitted for convenience of illustration.

FIG. 3 is a fragmentary side elevation thereof shown in enlarged scale, an intermediate portion being broken away and omitted to indicate indeterminate length.

FIG. 4 is a top plan view of FIG. 3, also shown in enlarged scale, a corresponding intermediate portion broken away and omitted for convenience of illustration.

FIG. 5 is an end elevation thereof as viewed from the right of FIG. 1 and FIG. 3.

It is to be understood that the broken away and omitted portion of each of FIG. 1 and FIG. 2 is continued over the length of the live poultry mover.
